UNITED STATES PATENT OFFICE.

CHARLES BRESLOFF, OF NEW YORK, N. Y.

DESIGN FOR AN ELECTRIC-CHANDELIER ARM.

55,242.

Specification for Design.

Patented May 25, 1920.

Application filed March 12, 1920. Serial No. 365,349. Term of patent 14 years.

To all whom it may concern:

Be it known that I, CHARLES BRESLOFF, a citizen of Russia, residing at 442 Bradford street, in the county of Kings, city and State of New York, have invented a new and original and ornamental Design for an Electric-Chandelier Arm, of which the following is a specification, reference being had to the accompanying drawing, forming a part thereof.

Figure 1 in the drawing shows a front perspective view.

Fig. 2 in the drawing shows a side perspective view.

I claim:

A new and ornamental design for an electric chandelier arm substantially as shown.

CHARLES BRESLOFF.
